FLOW RESTRICTOR

John O. Hruby, Jr., Burbank, Calif., assignor to Rain Jet Corporation, Burbank, Calif., a corporation of California

Filed Sept. 12, 1958, Ser. No. 760,686

7 Claims. (Cl. 251—216)

This invention relates to restrictors for controlling flow of fluids through tubular conduits.

While the invention may be employed advantageously for various conduit installations, including, for example, heating systems and overhead sprinkler systems, I have chosen to illustrate and describe the invention as the same may be embodied in a lawn sprinkler system, for when so described the advantages of the invention become readily apparent.

In the installation of conventional lawn sprinkler systems, a pipe leading from a waterline is laid into the ground and a plurality of short risers are connected to it for attaching sprinkler heads to the pipe. The flow restrictors of this invention are adapted to be mounted within or in alignment with such risers thereby to enable control of the size of sprays from the sprinkler heads.

It is a general object of this invention to provide an improved restrictor which may be adjusted easily when positioned in a conduit to obtain a desired rate of flow in the conduit.

Another object of this invention is to provide a restrictor of the above mentioned character which is simple in construction, easy to install, efficient in operation, and of relatively low cost.

Further objects and advantages of this invention will appear in the following part of this specification wherein the details of construction and mode of operation of a preferred embodiment are described with reference to the accompanying drawing, in which:

Fig. 1 is a side elevation, with certain parts being shown in central vertical section, of a portion of a lawn sprinkler system having a restrictor of this invention contained therein;

Fig. 2 is a central vertical section through the restrictor taken along line 2—2 of Fig. 1;

Fig. 3 is another central vertical section through the restrictor taken perpendicular to the section of Fig. 2; and

Fig. 4 is a cross section taken on line 4—4 of Fig. 3.

Referring to the drawing in greater detail, there is shown a pipe 10 and a pipe-T 11 of a lawn sprinkler system. Extending vertically above the pipe-T 11 is a riser pipe 12 having a sprinkler head 13 mounted upon the upper end thereof. The sprinkler head is shown for illustration purposes only, and may be of the type described in United States Letters Patent No. 2,639,191, issued May 19, 1953.

A restrictor embodying this invention and designated, generally, by reference numeral 16 is positioned in the pipe-T 11 as an extension of the riser 12, the illustrated restrictor constituting the upstream (lower) end of the riser. The restrictor comprises a tubular body 18 having a male end portion 19 which is externally screw-threaded for engagement with internal screw threads 20 in the pipe-T 11. The lower annular end surface of the body is designated by numeral 21.

A downstream (upper) end portion 22 of the restrictor body comprises a female fitting which is internally screw-

2

threaded at 23 for receiving the lower end of the pipe 12. From the screw threads 23, the inside of the body is of reduced diameter to define an inclined annular shoulder 24 and a cylindrical inside wall 25 extending coaxially in the body. Near the upstream (lower) end of the body there is a chamfered annular shoulder 26 extending inwardly from the lower end of the cylindrical wall 25 to make the inside of the body of still smaller inside diameter in an internally screw-threaded end portion or flange 27.

The body receives a solid plug 29 comprising a cylindrical head portion 30 and a cylindrical stem portion 31. The lower end face of the plug is designated by reference numeral 32 and its upper surface by numeral 33. Numerical 34 designates the cylindrical side walls of the head portion. The stem portion is externally screw-threaded throughout the length thereof for mating with the screw threads in the inside flange 27. A frusto-conical shoulder 35 defines the upper end of the stem portion of the plug and the lower end of the head portion of the plug and seats upon the chamfered shoulder 26 in the body when the plug is turned down in the body to its lowermost position.

The plug is preferably formed from relatively hard plastics, e.g. nylon, whereby the same has resiliency. The cylindrical side walls of the head portion of the plug are made to a diameter such that the head portion will fit slidably but tightly against the cylindrical inside wall 25 of the body to prevent unintended rotation of the plug in the body.

A diagonally extending groove 38 is formed in the head portion of the plug and is open to the upper surface 33 for accommodating the tool end of a screwdriver (not shown) for turning the plug in the restrictor body. Such groove or slot 38 preferably extends at least down to the level of the shoulder 35 thus dividing the head portion to increase the resiliency thereof for fitting down tight in the cylindrical wall 25 of the body.

The plug has two longitudinally extending grooves 40 and 41 formed in the stem portion thereof, open in the outside surface of the stem portion and being continuous with the head groove 38 whereby they leave a rib 42 between them. These stem grooves terminate in a rounded end portion at 43 above the lower end face 32 of the plug. The stem and its grooves 40 and 41 are of a length such that the lower end portion of the stem below the ends 43 of the stem grooves will be engaged in the screw threads of the inside flange 27 of the body before the cylindrical side walls of the head portion engage in the cylindrical inside wall 25 of the body, as appears in Fig. 3 of the drawing. As the plug is turned down in the body, the plug head becomes received within the cylindrical wall 25 to bind the plug in the body. Further turning of the plug will cause the lower ends of the grooves 40 and 41 to become exposed beyond the lower end 21 of the body, thereby to provide passageways through the plug. The size of openings of such passageways is controlled by rotation of the plug in the body resulting in increasing or decreasing the extent to which the stem grooves are exposed beyond the lower end of the body.

The restrictors of this invention may be installed in a lawn sprinkler system and adjusted to equalize the spray from the several sprinkler heads of the sprinkler system or to cause one sprinkler head to cover a larger or smaller area than others as desired and as explained in United States Letters Patent No. 2,810,607.

While the instant invention has been shown and described herein, in what is conceived to be the most practical and preferred embodiment, it is recognized that departures may be made therefrom within the scope of the invention, which is therefore not to be limited to the de-

tails disclosed herein, but is to be accorded the full scope of the claims.

What I claim is:

1. A flow restrictor for a conduit comprising an open-ended tubular body adapted to define a section of the conduit, the body having opposite ends which define end openings of the body, respectively, a cylindrical inside wall portion of circular cross section, and an inwardly extending annular shoulder portion spaced axially from one end of the body, said shoulder portion being internally screw-threaded; a plug having a head portion and a stem portion and an end surface for the head portion and an end surface for the stem portion, said end surfaces being opposite end surfaces of the plug, the head portion having a cylindrical side wall extending coaxially of the plug and being of just slightly diameter than the stem portion such as to be tightly slidably axially in said inside wall, the stem portion being externally screw-threaded for mating with the screw threads of said shoulder portion, the plug having a longitudinally extending groove formed therein, said groove being open in the head end surface of the plug and open in the side walls of the head and stem portions and terminating short of the stem end surface of the plug, whereby as the plug is rotated in the body said groove becomes exposed in the side wall of the stem portion beyond said shoulder portion and said head portion fits tightly in the cylindrical wall portion of the body to prevent unintended rotation of the plug in the body, and the groove provides for fluid flow to within the body opening in said one end of the body.

2. A flow restrictor according to claim 1 in which said plug is formed of nylon.

3. A flow restrictor for a conduit comprising an open-ended tubular body adapted to be mounted in the conduit and having an upstream end surface, a downstream end surface, a cylindrical inside wall portion of circular cross section disposed coaxially of the body and intermediate its ends, and an inwardly extending annular shoulder portion proximate its upstream end, said shoulder portion being internally screw-threaded; an elongate plug having a downstream end, an upstream end, a stem portion extending from the upstream end of the plug, and a head portion at the downstream end of the plug, the head portion having a cylindrical side wall extending coaxially of the plug and being of just slightly greater diameter than the stem portion such as to be tightly slidably axially in said inside wall, the stem portion being externally screw-threaded for mating with the screw threads of said shoulder portion, the plug having a longitudinally extending groove formed therein, said groove being open in the downstream end surface of the plug and open in the side walls of the head and stem portions and terminating short of the upstream end surface of the plug, whereby as the plug is rotated in the body to

move in an upstream direction with respect to the body said groove becomes exposed beyond said shoulder portion and said head portion fits tightly in the cylindrical wall of the body to prevent unintended rotation of the plug in the body, and the groove provides for flow of fluid to within the downstream end portion of the body.

4. A flow restrictor for a conduit comprising an open-ended tubular body adapted to be mounted in the conduit and having an upstream end surface, a downstream end surface, a cylindrical inside wall portion of circular cross section disposed coaxially of the body and intermediate its ends, and an inwardly extending annular shoulder portion proximate its upstream end, said shoulder portion being internally screw-threaded; an elongate plug having a downstream end, an upstream end, a stem portion extending from the upstream end of the plug, and a head portion at the downstream end of the plug, the head portion having a cylindrical side wall extending coaxially of the plug and being of just slightly greater diameter than the stem portion such as to be tightly slidably axially in said inside wall, the stem portion being externally screw-threaded for mating with the screw threads of said shoulder portion, the plug having two diametrically opposed grooves formed therein and extending longitudinally of the plug, said grooves being open in the downstream end surface of the plug and open in the side walls of the head and stem portions and terminating short of the upstream end surface of the plug, whereby as the plug is rotated in the body to move in an upstream direction with respect to the body said grooves become exposed beyond said shoulder portion and said head portion fits tightly in the cylindrical wall of the body to prevent unintended rotation of the plug in the body and said grooves provide for flow of fluid to within the downstream end portion of the body.

5. A restrictor according to claim 4 in which said grooves terminate at an equal distance from the upstream end surface of the plug.

6. A restrictor according to claim 4 and comprising a diametrically extending slot formed in the downstream end surface of the plug and being continuous with said grooves.

7. A restrictor according to claim 6 in which said slot extends to a depth substantially equal to the axial length of the side wall of said head portion.
